UNITED STATES PATENT OFFICE

162,537

CHRISTMAS STOCKING

Helen Gould Hathaway, Kansas City, Mo.

Application August 12, 1949, Serial No. 4,438

Term of patent 3½ years

(Cl. D47—7)

To all whom it may concern:

Be it known that I, Helen Gould Hathaway, a citizen of the United States, residing at Kansas City, in the county of Jackson and State of Missouri, have invented a new, original, and ornamental Design for a Christmas Stocking, of which the following are specifications, reference being had to the accompanying drawing, forming part thereof.

Fig. 1 is a perspective view of the Christmas stocking, showing my new design.

Fig. 2 is a rear elevation thereof.

Fig. 3 is a front elevation thereof.

I claim:

The ornamental design for a Christmas stocking, as shown.

HELEN GOULD HATHAWAY.
